(57) CLAIM

The ornamental design for a cosmetic package, as shown and described.

DESCRIPTION

FIG. 1 is a perspective front view of a cosmetic package, embodying the new design;

FIG. 2 is a front view of the design shown in FIG. 1; the back view of the design shown in FIG. 1 is the same; FIG. 3 is a right side view of the design shown in FIG. 1; the left side view of the design shown in FIG. 1 is the same; FIG. 4 is a bottom view of the design shown in FIG. 1; and FIG. 5 is a top view of the design shown in FIG. 1.

The two different areas (i.e., lighter and heavier densities) of diagonal line shading in these figures represent two different shades of the color green.

FIG. 6 is a perspective front view of another embodiment of a cosmetic package, embodying the new design;

FIG. 7 is a front view of the design shown in FIG. 6;

FIG. 8 is a back view of the design shown in FIG. 6;

FIG. 9 is a right side view of the design shown in FIG. 6;

FIG. 10 is a bottom view of the design shown in FIG. 6; and FIG. 11 is a top view of the design shown in FIG. 6.

The two different areas (i.e., lighter and heavier densities) of diagonal line shading in these figures represent two different shades of the color green.

FIG. 12 is a perspective front view of another embodiment of a cosmetic package, embodying the new design;

FIG. 13 is a front view of the design shown in FIG. 12;

FIG. 14 is a back view of the design shown in FIG. 12;

FIG. 15 is a right side view of the design shown in FIG. 12;

FIG. 16 is a bottom view of the design shown in FIG. 12; and FIG. 17 is a top view of the design shown in FIG. 12.

The two different areas (i.e., lighter and heavier densities) of diagonal line shading in these figures represent two different shades of the color green.

FIG. 18 is a perspective front view of another embodiment of a cosmetic package, embodying the new design;

FIG. 19 is a front view of the design shown in FIG. 18;

FIG. 20 is a back view of the design shown in FIG. 18;

FIG. 21 is a right side view of the design shown in FIG. 18;

FIG. 22 is a bottom view of the design shown in FIG. 18; and FIG. 23 is a top view of the design shown in FIG. 18.

The two different areas (i.e., lighter and heavier densities) of diagonal line shading in these figures represent two different shades of the color green.

FIG. 24 is a perspective front view of another embodiment of a cosmetic package, embodying the new design;

FIG. 25 is a front view of the design shown in FIG. 24;

FIG. 26 is a back view of the design shown in FIG. 24;

FIG. 27 is a right side view of the design shown in FIG. 24;

FIG. 28 is a bottom view of the design shown in FIG. 24; and, FIG. 29 is a top view of the design shown in FIG. 24.
